PROTECTIVE COVER FOR COUNTER CORNERS

Viola M. Berchert, 3360 Pittsview Drive,
Ann Arbor, Mich. 48104

Filed Feb. 18, 1971, Ser. No. 116,731

Term of patent 14 years

Int. Cl. D8—09

U.S. Cl. D8—263

FIG. 1 is a view in perspective of the protective cover for counter corners of my design;

FIG. 2 is a top view thereof;

FIG. 3 is a side view in elevation;

FIG. 4 is a bottom view;

FIG. 5 is a cross-sectional view taken along line 5—5 of FIG. 3; and

FIG. 6 is a cross-sectional view taken along line 6—6 of FIG. 1.

I claim:

The ornamental design for protective cover for counter corners, as shown.
